LOAD MANEUVERING APPARATUS

Wellington C. Carl, Churchill, and Howard A. Zollinger, Monroeville, Pa., assignors to Westinghouse Electric Corporation, Pittsburgh, Pa., a corporation of Pennsylvania

Filed Jan. 25, 1963, Ser. No. 253,809
7 Claims. (Cl. 214—14)

This invention relates to apparatus for maneuvering, i.e., holding, positioning or moving, a load between two stations which are subject to relative movement between each other. This invention is particularly useful in maintaining a constant position or constant velocity of a load being held or transferred between a floating vessel and another station such as a dock, another floating vessel, an underwater structure, the bottom of the sea, or any other selected reference point.

When a load is being lifted from a ship's deck by a crane located on the dock, if the crane operator misjudges the ship's position due to wave movement and hoist speed, the ship may rise on the wave and hit the load before it is clear. On the other hand, when a load is being placed on the ship the operator must try to judge the roll and pitch of the ship, or the load may hit the deck too hard. In either case damage to both the load and ship is possible.

For convenience, the station on which the load moving apparatus such as a crane is located, will be referred to as the "active" station, while the other station will be referred to as the "passive" station. In the ship and dock example, the dock is the active station if the crane is on the dock. The ship in that case is the passive station.

One aspect of the present invention contemplates apparatus for controlling the movement of a load between two stations to control the load to desired constant velocity relative to the passive station while the stations are subject to relative movement between each other. This may include the case where the desired constant velocity is zero, in which case the position of the load is held constant relative to the passive station. This is accomplished in accordance with one embodiment of the invention by a hoist controlled by resultant forces produced from a desired speed command signal, an actual load speed signal, and a signal which is a function of the relative motion between the stations. More specifically, in accordance with one embodiment, the speed regulated hoist is made responsive to a signal which is a function of the relative motion between said stations thereby to compensate for such relative motion.

It is therefore an object of the present invention to provide apparatus for compensating for the relative motion between two stations between which a load is being maneuvered.

Another object of the invention is to provide apparatus for maneuvering a load between active and passive stations at a constant desired velocity relative to the passive station, while there is relative movement between the stations.

Another object is directed to reducing or eliminating the effect of relative motion between active and passive stations on the velocity or position of a load relative to the passive station.

Other objects and advantages of the present invention will become apparent from the following description taken in connection with the accompanying drawing, wherein there is illustrated a preferred form of the invention as embodied in a hoist system for transferring loads between a dock and a floating vessel. In order to simplify the illustration of the invention, auxiliary equipment, such as breakers, relays, electrical interlocks, brakes, etc., usually

found in apparatus of the character described, is not shown.

In the drawing, there is shown a diagrammatic representation of a crane 10 mounted on a dock 12 for transferring a load 14 between the dock and a floating vessel 16. The crane includes a load lifting cable 18 reeved around a sheave 20 on the outer end of a boom 22, and reeled on a drum 24 driven by a reversible drive 26. The drive 26 includes a motor 28 mounted on the crane and a control system 30 for controlling the speed and direction of the motor, and thereby of the load, by controlling the electric power supplied from a suitable source to the motor. By way of example, the motor 28 is shown as a three-phase squirrel cage motor supplied from supply lines L1, L2 and L3 connected to a source of three-phase power (not shown).

The control system 30 includes a variable impedance arrangement 34 interposed in the motor 28 supply lines, and controlled in response to a desired load speed reference or command signal A, an actual load speed signal B, and a signal C representing the relative motion between the ship and the dock. These signals are applied to a summing circuit 36 which controls the variable impedance arrangement 34 to provide speed and reversing control.

More specifically, power line L1 is connected through the main winding 38 of a saturable reactor 40 to a terminal T1 of the motor 28. Line L1 is also connected through the main winding 41 of a saturable reactor 42 to a terminal T3 of motor 28. In like manner line L3 is connected to terminals T1 and T3 through the main windings 45 and 47 of saturable reactors 44 and 46 respectively. For convenience, reactor 40 and 46 will be referred to as the "hoist" reactors while reactors 42 and 44 will be referred to as the "lowering" reactors. Line L2 is connected directly to terminal T2 of the motor.

Control windings 48 and 50 of the "hoist" reactors 40 and 46 are connected together to the D.C. output 52 of a magnetic amplifier 62 which may conveniently be referred to as the "hoist" pilot amplifier. Likewise, control windings 64 and 66 of the lowering reactors 42 and 44 are connected together to the D.C. output 67 of a magnetic amplifier 68 which may conveniently be referred to as the "lowering" pilot amplifier. It should be apparent that the hoist reactors are driven in unison in the same direction by the hoist amplifier 62, either up or down, and that the lowering reactors are driven together in the same direction either up or down by the lowering amplifier 68.

Amplifiers 62 and 68 are provided with control windings 70 and 72 respectively connected in series opposition so that a common signal flowing through the control windings affects the amplifiers in opposite sense. More specifically, a common control signal through the control windings 70 and 72 will tend to drive the amplifiers 62 and 68 in opposite directions, that is drive one up while the other is driven down. A bias circuit 74 is arranged to bias the hoist and the lowering amplifiers to cutoff at quiescent. Thus with no signal in the control windings 70 and 72 the respective amplifiers 62 and 68 do not produce an output and the hoist and lowering reactors will be unsaturated, each presenting maximum impedance in its line.

The polarity dot convention employed in the drawing in connection with the hoist and lowering amplifiers signifies that a current of positive polarity applied at the dotted end of a winding will tend to drive the amplifier up, the converse being true when a signal of negative polarity is applied to the dotted end of a winding.

From the foregoing it should be apparent that a net positive signal on a line 76 connected to the control windings 70 and 72 will drive the output of the hoist amplifier 62 upward and tend to drive the output of the lowering

amplifier 68 down. This saturates the hoisting reactors 40 and 46, while the lowering reactors 42 and 44 remain unsaturated. Thus the impedance of reactors 40 and 46 are reduced, thereby effectively connecting line L1 to terminal T1 and line L3 to terminal T3, thus providing a particular phase rotation to drive the hoist motor 28 in the hoist direction. In the meantime reactors 42 and 44 remain at their maximum impedance, and as a result the circuits from L1 to terminal T3 and from L3 to terminal T1 are substantially open circuits.

On the other hand, if a negative signal is applied to the line 76 the lowering amplifier 68 is driven up while the hoist amplifier 62 is held to no output. These conditions saturate the lowering reactors 42 and 44 while the hoist reactors 40 and 46 remain unsaturated, and as a result line L1 is effectively connected to terminal T3 of the hoist motor 28 and line L3 is effectively connected to terminal T1 of the motor thereby producing a reversed phase rotation to drive the hoist motor in the lowering direction.

In addition, the saturation of the hoist and lowering reactors may be controlled between zero and maximum, thereby controlling the motor torque or speed in the chosen direction by varying its primary voltage.

Control windings 70 and 72 of the hoist and lowering amplifiers are connected in the summing circuit 36 in series opposition as hereinbefore mentioned whereby the net signals developed by the summing circuit 36 are supplied in "push pull" to the control windings of the hoist and lowering amplifiers 62 and 68.

Connected into the summing circuit 36 is a desired speed reference signal source 80 for supplying to the summing circuit a desired speed reference or command signal A representing a desired direction and speed of the load 14. In the source 80 there is a split potentiometer 82 connected across a D.C. source, for example the battery shown at 84. A fixed center tap 86 on the potentiometer is connected to a conductor 87 of the mixing circuit 36. The potentiometer 82 is provided with a movable tap 88 mechanically linked to a master controller handle 90 and electrically connected through conductor 76 to the dot end of control winding 70 of the hoist amplifier 62. The controller handle 90 also operates a drum switch 91 in unison with the pot arm 88.

When the potentiometer arm 88 is moved to the hoist side by the control handle 90, a positive voltage is applied to line 76. On the other hand, when the arm 88 is moved to the lowering side, a negative voltage is applied to line 76. The magnitude of the output voltage of source 80, adjustable by means of handle 90, is selected to correspond with the desired speed of the motor and load movement. Thus the speed of load movement will be dependent on the magnitude of the voltage supplied by source 80, which in turn is dependent on the position of the potentiometer arm 88 as determined by the handle 90.

A signal B representing the actual speed of the load 14 relative to the crane 10 is injected into the summing circuit 36 by a D.C. tachometer 94, which is mechanically coupled to the output shaft 95 of the hoist motor 28. This tachometer provides an output voltage with a magnitude proportional to the motor speed and a polarity dependent on the direction of motor rotation.

In the particular arrangement shown, and as indicated by the legends under the tachometer, the tachometer 94 generates a positive voltage at its output terminal 96 when the hoist motor 28 is hoisting, and a negative voltage at terminal 96 when the hoist motor 28 is lowering. One output terminal 96 of tachometer 94 is connected through a current limiting resistor 98 to the dot end of the control winding 72 of the lower pilot amplifier 68. The other output terminal 100 of this tachometer is connected through a resistor 102 to the line 87.

At 104 there is shown a ship's motion reference circuit which, when connected into the summing circuit 36 by a switch 106, supplies to the summing circuit a signal

5 C which is proportional to the velocity of the relative vertical movement between the ship 16 and the crane 22. Included in the circuit 104 is a D.C. tachometer 108 mechanically driven by a sheave 110 rotatably mounted on the crane boom 22. The pulley 110 is rotated by the vertical motion of the vessel 16 in one or the other direction by means of a tag line 112 reeved around the pulley 110 and secured at one end 114 to the ship 16, while the free end of the line is weighted at 116 to maintain constant tension on the line. A suitable guide pulley 4 may be employed to keep the weighted side of the line free from entanglement. Such a guide pulley may be fastened on the crane boom 22 or the dock 12, as shown.

One output terminal 120 of the ship motion tachometer 108 is connected to one side of switch 106, the other side of the switch being connected to a junction 122 between one end of resistor 102 and the output terminal 100 of the load velocity tachometer 94. The other output terminal 124 of the ship's motion tachometer 108 is connected through a one way valve 126 to the other end of resistor 102. Means for shunting the one way valve 126 during the lowering operation is provided by a switch segment 130 of the drum switch 91 which segment shorts a set of contacts 132 when the controller handle 90 is moved to the lowering position. Contacts 132 are connected on opposite sides of the one way valve 126. Thus, when switch 106 is closed the tachometer 108 is connected across the resistor 102 either through the one way valve 126 or through the shorted contacts 132 around the valve, as the case may be. In either event, a signal C representing and responsive to relative vertical motion between the vessel 16 and the crane boom 22 is injected into the summing circuit 36. The polarity of such a signal will be dependent upon the direction of the relative movement between the vessel and the dock, while the magnitude of the signal will be proportional to the speed of such relative movement.

40 In the specific arrangement shown by way of example, and as appears in the legends alongside the tachometer 108, this tachometer produces a positive voltage at its terminal 120 when the ship is falling (or into a wave trough), and a negative voltage at terminal 120 when the ship is rising on a wave.

Operation without the ship's motion reference

45 The system illustrated with only the command signal source 80 and the load speed reference source 94 connected into the summing circuit 36, but without the ship's motion reference circuit 104, constitutes a well known speed regulated hoist system, i.e., the load speed for any given command or reference speed is maintained constant relative to the crane and dock 12. The operation of this prior art portion of the system will now be briefly described.

50 As hereinbefore stated the command or desired speed reference signal A from the command source 80, for any given command direction is opposed in the summing circuit 36 by the actual motor speed signal B produced by tachometer 94. The differentially combined signals A and B are applied to the control windings of the hoist and lower amplifiers, whereby these amplifiers respond to the differential between signals A and B, which is the regulating "error" in the system. The magnitude and polarity of the command signal A from the command source 80 is dependent on the desired speed and direction of the command. The magnitude and polarity of the output of tachometer 94 is dependent on the speed and direction of rotation of the hoist motor 28. Thus, the command signal A is proportional to desired speed, while the actual speed signal from tachometer 94 is proportional to the speed of the hoist motor.

55 To raise the load 14, the master control handle 90 is moved into the hoist sector of the controller range to a selected position corresponding to the desired speed, for example, to the second hoist position. Movement of the

handle 90 into the hoist sector (leftward) moves the drum switch 91 and the potentiometer arm 88 in unison to the left or the hoist sector of the controller. In this sector, potentiometer arm 88 taps into the "positive" side of hoist sector of the potentiometer 82 to provide a positive command signal A to the dot end of control winding 72, the magnitude of the signal corresponding to the selected command speed. This drives the output of the hoist amplifier 62 up to saturate the hoist reactors 40 and 46. Since a signal of this polarity tends to drive the lowering amplifier 68 down, this amplifier is held at cutoff and the lowering reactors 46 and 50 remain unsaturated and at maximum impedance. The hoist reactors 40 and 46 are saturated to a degree dependent on the magnitude of the command signal A. As a result, motor 28 is excited in the proper phase sequence to rotate in the hoist direction. As the speed of the hoist motor increases, the output voltage of the tachometer 94, which is opposed to the command signal, increases until equilibrium is reached where-in enough excitation is supplied to the motor to produce the requisite torque to maintain the selected command speed.

If for any reason the motor 28 should run faster than the command speed, the tachometer 94 voltage will be greater than the command signal A and the polarity of the resulting error signal will be such as to apply positive voltage to the dot end of control winding 72 and negative voltage to the dot end of control winding 70. The net result of this is a reversal of the phase sequence applied to the motor and a consequent application of countertorque within the motor or "plugging," thus, slowing the motor down until equilibrium is reached at the proper speed and torque.

To lower the load, the command signal A is reversed in polarity by moving the master control handle 90 to the lowering sector, thus moving the potentiometer arm 88 to that side of the potentiometer which will produce a positive signal at the dot end of control winding 72 and a negative signal at the dot end of control winding 70, thereby driving the output of the lowering amplifier 68 upward to produce the proper phase sequence at the motor 28 terminals to rotate the motor in the lowering direction.

In the lowering direction tachometer 94 produces an output voltage which is positive at terminal 100 thereby opposing the command signal A which for the lowering direction is negative at the potentiometer arm 88 and positive at the tap 86. At the speed of the load increases in the lowering direction, the tachometer 94 output voltage increases. If in lowering, the load tends to overtake the motor, the tachometer 94 voltage will exceed the command signal A thereby saturating the hoist reactors to provide sufficient countertorque to keep the load at the command speed.

In summary, the system whose operation has just been described is known as a speed regulated system wherein the speed of the hoist motor is regulated or maintained constant for any given command signal. In this system the load movement is maintained at a constant speed relative to the crane 22 and dock 12 for a given command speed. It can also be seen from the above operational description that, although the load speed is constant relative to the crane and crane support, the speed of the load relative to the ship is undesirably variable due to the rise and fall of the ship because of wave action. The present invention as will now be more specifically described is directed to a reduction or elimination of the variation in speed of the load relative to the ship due to the relative vertical motion between the ship and the crane.

Operation with the ship's motion signal

To minimize the effect of the ship's motion in accordance with one embodiment of the invention, the ship mo-

tion reference circuit 104 is added to the summing circuit 36 by closing switch 106.

In hoisting a load, the direction of relative movement between load and ship is away from each other, that is, in the Opening direction. Likewise, when wave motion causes the ship to fall away from the load, the relative motion between the ship and the crane and also between the ship and the load is in the Opening direction. On the other hand, when the load is being lowered to the ship, the direction of relative movement between ship and load is in the Closing direction. Likewise, if wave motion causes the ship to rise toward the load, the direction of relative movement between the ship and the crane and between the ship and the load is in the Closing direction.

When it is desired to compensate for the relative motion between the ship and the crane, the switch 106 is closed. The polarity relation of the ship motion reference circuit 104 to the rest of the summing circuit 36 is such that the command signal A from the desired speed reference source 30 and the ship motion signal C from the ship's motion reference source 104 are in mutually aiding relation when the direction of relative movement between the ship and the crane is opposite to the commanded direction of relative movement between the load and the ship. In other words, for this circumstance the signals A and C have similarly sensed control effect on the control system 30. On the other hand, signals A and C are in mutually opposing relation providing oppositely sensed control effects on the control system 30 when the relative movement between the ship and the crane is in the same direction as the commanded relative movement between the load and the ship.

As hereinbefore stated, when the ship is rising, that is, when the direction of the relative movement between the ship and the crane is in the Closing direction, the ship's motion tachometer 103 provides a negative output at its terminal 120, the terminal 124 then being positive. However, when the ship is falling, that is, when the relative movement between the ship and the crane is in the Opening direction, the output of the ship motion tachometer 103 is positive at terminal 120 and negative at terminal 124.

From the above, it should be apparent that the ship motion signal C from the tachometer 103 aids the command signal A from the source 30 when the relative movement between the ship and the crane is in the direction tending to oppose the purpose of the command signal A, and signal C opposes signal A when the direction of relative movement between the ship and the crane aids the purpose of the command signal A. It should be apparent that a falling ship opposes the purpose of a lowering command, while a rising ship aids the purpose of a lowering command. Also, a hoist command is opposed by a rising ship, and aided by a falling ship.

These relations reverse when the position of the crane is reversed, that is when the crane is on the ship. In the latter case a falling ship aids the purpose of a lowering command, while a rising ship opposes the purpose of a lowering command. Also with the crane on the ship, a hoist command is aided by a rising ship, and opposed by a falling ship.

The operation will now be considered in more specific detail. Suppose that a load is to be transferred from the dock to the ship. With the switch 106 open, the crane operator swings the crane 22 around its vertical pivot to a position over the load on the dock. The load is hooked to the line 18 and the crane operator raises the load by operating the master control 90 to the hoist side, the load is then held in a hoisted position by just enough hoist command signal A to provide stall torque, and the crane is swung around its vertical pivot to position the load over the ship. The crane operator then closes switch 106. The drive system now will follow the ship's motion signal and tend to maintain a constant distance between the load and the ship.

In order to lower the load to the ship's deck the crane operator moves the master control 90 to the lowering side to provide a lowering command signal which is negative at the dot end of the control winding 70. In this position of control 90, contacts 132 are bridged by switch segment 130 to shunt the one way valve 126. As the load starts to move down, the speed feedback tachometer 94 puts out a negative signal at its terminal 96 which opposes the command signal. If in the meantime the ship is rising, the ship movement tachometer 108 generates a negative signal at its terminal 120 which opposes the command signal and forces the drive to run slower. If, as the ship is rising, the ship movement tachometer signal C exceeds the command signal A the load will actually be hoisted. On the other hand, if, as the load is being lowered, the ship is falling, the ship movement tachometer 108 output signal C will be positive at its terminal 120 thus aiding the command signal A, thereby causing the drive to lower faster. Thus the application of the ship motion signal C to the regulating loop regulates the drive to maintain a constant speed between the load 14 and the ship 16 for any selected command speed.

When it is desired to lift a load from the ship, the crane operator moves the master controller 90 to the hoist position applying a positive signal to the dot end of control winding 70. As the load rises, the speed feedback tachometer 94 generates a positive signal at its terminal 96 tending to cancel the command signal to keep the drive at a constant speed relative to the dock. If the ship rises as the load is being hoisted, the ship movement tachometer 108 generates a negative signal at its terminal 120 thus aiding the command signal and forcing the drive to hoist faster, thereby to maintain constant hoisting speed between the load 14 and the ship 16.

It will be noted that when the controller 90 is in the hoist position, the contacts 132 in the drum switch are open so that the ship motion tachometer 108 output is applied to the summing circuit 36 through the one way valve 126. This valve is so poled or oriented that it blocks the output of the ship motion tachometer 108 when the ship is falling, thus not slowing down the hoist as it is leaving the ship. This is made effective only in hoisting, where it is useful, by leaving the contacts 132 open on hoisting and closing them on lowering.

As seen from the description herein, the present invention makes the motor 28 hoist or lower at a speed necessary to keep the load moving with respect to the ship at the speed set by the master control 90 regardless of the up and down movement of the ship.

Although above water stations have been illustrated, the invention is also very useful in the case where a hoist on a vessel floating on the surface of the water lowers and hoists objects to and from an underwater station such as the bottom of the sea, an underwater structure, or any selected underwater reference level. The invention helps to avoid sudden load changes due to the friction or retarding effects of the water as the ship rises and falls with the waves or swells.

The invention is not limited to the particular reversible drive and control therefor shown by way of example. Other suitable reversible drives and controls therefor may be employed in practicing the invention. Likewise, the ship motion signal C may be obtained by other suitable apparatus, for example, gyroscopic systems, sonar systems, or any other apparatus which will provide a signal responsive to the relative movement between the ship and the crane. To a great extent the particular speed of response and the degree of constancy that may be desired will govern the selection of system types, drives and control components. Thus, it is to be understood that the herein described arrangements are simply illustrative of the principles of the invention, and other embodiments and applications are within the spirit and scope of the invention.

We claim as our invention:

1. Hoisting apparatus for transferring a load between two stations while said stations are subject to relative vertical motion between each other, said apparatus comprising load moving means including adjustable speed reversible drive means, said drive means including a motor located on one of said stations for moving said load, control means coupled to said drive means for controlling the drive means to move said load in a direction and at a speed in accordance with signals supplied to said control means, means for providing and selectively supplying to said control means either of first and second command signals, said first command signal being of one sense and a particular magnitude for commanding the control means to operate said drive means to move the load in the hoist direction at a particular speed relative to the other of said stations, said second command signal being of opposite sense and a certain magnitude for said drive means to move the load in the lowering direction at a certain speed relative to said other station, means responsive to the relative motion between said stations for supplying a first speed signal proportional to the speed of said relative motion to said control means in said one sense when the relative motion is in a direction tending to close the gap between the load and said other station, and in said opposite sense when the relative motion is in the direction tending to widen the gap between the load and said other station, and means for providing and supplying to said control means a second speed signal representing the actual speed of said load relative to said one station and in a sense to oppose the selected one of said command signals being supplied to said control means, said control means being operable in response to said first and second speed signals and said selected one of said command signals to operate said drive means in a manner to maintain the commanded speed and direction of movement of said load relative to said other station.

2. In apparatus for transferring a load between two stations which are subject to relative movement therebetween, and wherein there is a reversible drive means for moving the load, said drive means including motor means located on one of said stations for moving said load, means for providing a command signal A indicative of a desired speed and direction of movement for said load relative to the other of said stations, means for providing a signal B dependent on the actual speed of said load relative to said one station, means responsive to the relative motion between said stations for providing a signal C proportional to the speed of and indicative of the direction of said relative motion between said stations, and control means coupled to said drive means and responsive to said signals A, B, and C for operating said drive means to maintain said desired speed and direction of movement of said load relative to said other station in conformance with the command of signal A, said signals A and B having opposed control effects when the load is moving in the direction dictated by the command signal A, said signals A and C being in mutually aiding relation when the relative movement between said stations is opposite to the commanded direction of relative movement between the load and said other station, said signals A and C being in mutually opposing relation when the relative movement between said stations is in the same direction as the commanded relative movement between the load and said other station.

3. The combination as in claim 2 wherein said control means comprises summing means in which signals A, B, and C are summed to produce a resultant control effect, and means responsive to said resultant control effect for controlling said drive means in accordance with the command represented by signal A.

4. Apparatus for moving a load between two stations which are subject to relative movement between each other, said apparatus comprising reversible drive means for moving said load in either direction between said stations.

tions, said drive means including motor means located on one of said stations for moving said load, means for providing a command signal A representing a desired speed and direction of movement for said load relative to the other of said stations, means for providing a signal B dependent on the actual speed of said motor means, tachometer generator means coupled to said stations and responsive to the relative movement therebetween for providing a signal C proportional to the speed of and indicative of the direction of relative movement between said stations, and control means coupled to said drive means and responsive to signals A, B, and C for operating said drive means to maintain said desired speed and direction of movement of said load relative to said other station in conformance with the command of signal A, said signals A and B having opposed control effects when the load is moving in the direction dictated by the command signal A, said signals A and C being in mutually aiding relation when the relative movement between said stations is opposite to the commanded direction of relative movement between the load and said other station, said signals A and C being in mutually opposing relation when the relative movement between said stations is in the same direction as the commanded relative movement between the load and said other station.

5. The combination as in claim 1 and further including means responsive to the selection of said first command signal for rendering said control means unresponsive to said relative motion when said motion is in the direction

15

20

25

30

tending to widen the gap between the load and said other station.

6. The combination as in claim 1 and further including a signal path along which said first speed signal is supplied to said control means, and circuit means responsive to the selection of said first command signal for effectively connecting a one way valve in series in said path whereby said control means is rendered unresponsive to said relative motion when the motion is in the direction tending to widen the gap between the load and said other station.

7. The combination as in claim 2 wherein said apparatus is a hoisting apparatus and the relative movement between the stations is vertical.
